ELECTRONIC MULTISELECTOR

The present patent of addition concerns improvements to multiselectors for switching stages in which contacts located at the cross-points are replaced by field-effect transistors and in which the said contacts are maintained in closed position electronically.

It is a well-known fact that field-effect or FET transistors, and in particular, metal-oxide-silicon FET transistors or "MOS transistors," have interesting characteristics when used as contact elements. In fact, the drain-source resistance of a MOS transistor, which constitutes the switched contact, is strictly voltage controlled so that there is a very good insulation of the control circuit with regard to the energized circuit.

Moreover, in this type of transistor, the drain-source resistance is higher than 10^7 ohms in the "high-impedance off" state and as low as 100 to 300 ohms in the "low impedance on" state which ensures very good operating characteristics as a contact element.

Another advantage of a multiselector equipped with MOS transistors as contact components lies in the fact that the selection and control circuits can also be designed with MOS transistors, both as regards the active components and the resistors. Consequently, multiselector matrices can be made with a capacity of 4×2 , 4×4 , 4×8 etc...cross-points in large scale integrated circuits which may comprise several hundred MOS transistors.

The object of the present invention is therefore to realize an elementary electronic multiselector in large scale integrated circuit.

It is a feature of the invention that a switching circuit is located at each cross-point between two perpendicular speech conductors made up of a vertical j and a horizontal k of the multiselector, that said circuit comprises first a contact element made up of a MOS transistor the source and drain of which are connected, respectively to exemplary conductors the vertical j and to the horizontal k and second, a holding flip-flop comprising transistors of the same type with its 1 output connected to the switching transistor grid so that, when said flip-flop is in the 1 state, the said transistor is conducting ("low impedance on" state) which corresponds to the closing of a pair of contacts connecting conductors j and k .

Another feature of the invention is that an elementary multiselector matrix comprises m verticals and n horizontals with which the same number of selection conductors are associated, that the selection of a particular vertical j is effected by applying a signal C_j to the vertical selection conductor c_j , that the selection of a particular horizontal k is effected by applying a signal $\bar{S}_k$ to the horizontal selection conductor s_k , that the matrix also comprises n "busy state" conductors $e_1, e_2, \dots, e_n$ associated with the horizontals, a signal E_k appearing on conductor e_k when at least one contact is closed to said horizontal, that in the rest position, signals $\bar{C}_j$ and $\bar{S}_k$ are applied to the selection inputs to ensure that the position of the holding flip-flop remains unchanged and that an inverter circuit to which signal C_j is applied delivers a signal $\bar{C}'_j$ delayed by a time t which is slightly longer than the switching time of the holding flip-flop.

Another feature of the invention is that, in order to close the switching circuit X_{jk} , first the horizontal selection of the said cross-point is effected by applying signal $\bar{S}_k$, second the vertical selection of the said point is effected by applying signal C_j which controls the opening of all the switching circuits associated with vertical j by resetting their holding flip-flops in the 0 state, third signal C_j is suppressed and signal $\bar{C}'_j$ sets in the 1 state the holding flip-flop of the selected switching circuit when signal $\bar{E}_k$ is present, and fourth signal $\bar{S}_k$ is suppressed so that the circuit receives signals $\bar{C}'_j$ and $\bar{S}_k$ which hold it in rest position.

Another feature of the invention is that the horizontal selection conductors are connected to the corresponding outputs of a shift register into which a code is introduced in series to control the horizontal selection in the matrix.

The above mentioned and other features and objects of this invention will become apparent by reference to the following description taken in conjunction with the accompanying drawings in which:

5 FIG. 1 shows a mode of setting up a speech path in an exchange comprising several selection stages;

FIG. 2 shows a symbolic diagram of a switching circuit;

10 FIG. 3 shows a diagram of an elementary multiselector matrix;

FIG. 4 shows a detailed diagram of a switching circuit and its associated circuits.

Before describing the invention, the main features and mode of operation of MOS transistors will be reviewed. All the transistors shown in FIG. 1 (with the exception of transistors T_1 and T_2) and in FIG. 4 are of this type.

A MOS transistor is almost completely symmetrical and the electrodes which operate as drain and source can be inverted without any disadvantages and without modifying its operation when it is used in logic circuits. Nevertheless the manufacturer defines, in the specifications, the electrodes which play the part of drain and source. Consequently, in the figures, the source is symbolized by an arrow as is the emitter of a bipolar transistor.

25 The operating voltages of a MOS-Ph transistor (type P, enhancement transistor) are defined as follows:

VT : threshold voltage;

VD : drain voltage;

VG : grid voltage.

30 All these voltages are measured with reference to that of the source ($VS=0$) and expressed in absolute values. Thus, a MOS transistor is in its "high impedance off" or "blocked" state when $VG \leq VT$. It then has a drain-source resistance RDS whose value is practically infinite (approximately 10^7 ohms).

35 A MOS transistor is "on" when $VG > VT$. It then behaves like a passive resistance whose value is

$$RDS = \frac{1}{K(VG - VT)} \quad (1)$$

40 K being a proportionality factor.

In this case there are two "on" regions:

the "low impedance on" region (or nonsaturated region) when

45 $VD < VG - VT$, with a drain-source resistance RDS of low value (50 to 200 ohms).

the "high impedance on" region (or saturated region) when

$VD \geq VG - VT$, with a resistance RDS of relatively high value.

If a MOS-Ph transistor has a threshold voltage of $VT=4$ v, and then a voltage $VG=0$ is applied to it, it becomes blocked. If a voltage $VG = -24$ v. and a voltage VD between zero and -20 volts is applied to said transistor, it sets into the on state. In practice, if good linearity of resistance RDS is required, must use lower values of VD . The resistance RDS then has a very low value and the transistor allows bidirectional transfer of analog or digital signals between drain and source.

50 MOS transistors are also used as resistors. Consequently large scale integrated circuits can be designed, this passive element operation being practicable for both types of conduction. For instance, if the transistor operates in the "low impedance on" region with a suitable bias ($VD < VG - VT$) and is connected in series with an inverter MOS transistor, either the voltage VD or the ground voltage appears at the connection common to both transistors depending on whether said inverter transistor is off ($VG \leq VT$) or on ($VG > VT$).

55 In the various figures accompanying this description, MOS transistors operating as active components are referenced "T" and those operating as load resistors bear the reference "R."

It is obvious that the use of MOS transistors as load resistors is only feasible where integrated technology is employed in which case they offer advantages from the point of view of manufacture. However, it is obvious that every MOS transistor referenced R and used as a resistor can be replaced by a conventional resistor of the same value.

We shall first recall with reference to FIG. 1 the mode of setting up a speech path in a switching center comprising, for instance, three selection stages *a*, *b* and *c*. In each of these stages this path uses MOS-Ph transistors *Ta*, *Tb* and *Tc* as well as bipolar NPN transistors *T1*, *T2* located at the ends of the path. Control signals *Aa*, *Ab* and *Ac* are applied to the MOS transistors via the inverters bearing the same references. The signals to be transmitted are applied to the input *D1* and collected at the output *D2*, the coupling being effected by the capacitors *K1* and *K2*.

When the grids of transistors *Ta*, *Tb* and *Tc* reach ground potential (inverters in position 0), said transistors become blocked. When these grids reach potential $-U_3$ (inverters in position 1) the said transistors may be conducting if transistors *T1* and *T2* are conducting.

We shall describe the operation in DC of the circuit of FIG. 1 assuming that inverters *Aa*, *Ab* and *Ac* are in position 1. It will be assumed that:

$$U_1=12 \text{ volts}$$

$$U_2=18 \text{ volts}$$

$$U_3=30 \text{ volts}$$

The voltage U_3 is used, in the circuits of FIG. 4, to set the transistors operating as load resistances in their "low impedance on" region.

Transistor *T1* is conducting ("low impedance on" region) with a collector current $I_1 \approx (U_2 - U_1)/R_1$.

Moreover, a potential difference U_3 is set up between the grid of transistor *Tc* and the base of transistor *T2* via the high impedance of the interelectrode capacity and the leakage resistance of transistor *Tc* so that both these transistors conduct. Similarly, transistors *Tb* and *Ta* conduct and a current $I_2 \approx I_1$ flows through them, as well as through *T1*, the load resistance of transistor *T1* then reaching a value of $R_e + 3R_{DS}$, in which R_e designates the emitter resistance of transistor *T2*.

In AC operation transistors *T1* and *T2* are in common base configuration with a very low input (approximately 10 ohms) and a very high output impedance (approximately 1 megohm). If α_1 and α_2 are the current gains of these transistors, and i_1 , i_2 the AC input and output currents, one has: $i_2 = \alpha_1 \alpha_2 i_1$. It can therefore be seen that, if high gain bipolar transistors are utilized, the output current differs by only a few percent from the input current and that it is independent from the resistance made up by the saturation resistances of MOS transistors *Ta*, *Tb* and *Tc* connected in series. Since the input impedance of transistor *T1* has a very low value, input current i_1 depends only from the value of resistor *R3* which comprises the line impedance. At the output, the load impedance is in parallel with resistor *R2* and current i_2 is shared by these two components according to their conductances.

The above described circuit only allows for transmission of information in one direction, i.e. from *D1* to *D2*, since the reverse voltage transfer ratio h_{12} of bipolar transistors *T1* and *T2* is very low. To achieve bidirectional transmission, two identical chains equipped with 2 wire—4 wire transformation must be utilized. In each selection stage, each contact element or cross-point comprises then two transistors controlled by the same switch.

FIG. 2 shows a symbolic diagram of such a cross-point designed for matrix assembly. When the cross-point is closed, the speech path is set up, in one direction, between horizontal *H'1* and vertical *V'1* and, in the other, between horizontal *H''1* and vertical *V''1*. To simplify the figure, the group of two horizontals will hereafter bear the reference *H1* and the group of two verticals the reference *V1*.

The cross-point is controlled by signals applied to the following conductors:

horizontal selection conductor *s1*,

vertical selection conductors *c1* and *c'1*,

busy line conductors *e1*.

Moreover, a conductor *a11* transmits information which characterizes the state of the cross-point, namely whether it is open or closed.

It will be noted that in this figure and in FIGS. 3 and 4, the conductors bear references comprising small letters followed by one or two digits and that they are encircled.

FIG. 3 shows a complete multiselector matrix according to 5 the invention comprising horizontals *H1*, *H2*...*Hk*...*Hn* and verticals *V1*, *V2*...*Vj*...*Vm*.

At each cross-point a switching circuit, like that represented in FIG. 2, is situated. Of the said circuits, those which are associated to horizontal *H1* bear references *X11*, *X21*...*Xm1* and those associated to horizontal *Hn* bear references *X1n*, *X2n*...*Xmn*.

Furthermore, the matrix comprises:

a shift register *R* comprising *n* stages the *n* outputs of which are connected to the horizontal selection conductors *s1*, *s2*...*sk*.... This register is also made with MOS-Ph transistors and can be, by way of an example, a dynamic shift register. Such a register, which comprises clock inputs *F1*, *F2*, signal input *M* and signal output *N*, enables to control the horizontal selection in the matrix by information applied to input *M* in series form.

A logic circuit per horizontal, namely, in the case of horizontal *H1*, circuit *G1* comprising NOR circuit *G'1* and inverter *G''1*.

Table I, below, indicates the various signals applied to the control conductors (signals bearing references in capital letters) as well as the corresponding voltage levels and the designation of said signals.

TABLE I

Conductor	Signal	Voltage	Designation
<i>c</i>	$\bar{C}$	0	
	<i>C</i>	$-U_2$	Connection signal.
<i>c1</i>	$\bar{C}'1$	0	
	<i>C'1</i>	$-U_2$	Delayed connection signal.
<i>s</i>	$\bar{S}$	0	
	<i>S</i>	$-U_2$	Non-selection signal.
<i>e</i>	$\bar{E}$	0	
	<i>E</i>	$-U_2$	Busy signal.
<i>a</i>	$\bar{A}$	0	
	<i>A</i>	$-U_2$	Closing signal.
<i>p</i>	$\bar{P}$	0	
	<i>P</i>	$-U_2$	Preselection signal.

For the purpose of simplification, the references of the conductors and signals, in this table, do not bear the digits identifying the horizontal and the vertical to which each cell is associated.

As can be seen from the table, a signal of amplitude $-U_2$ applied to selection conductor *sk* characterizes the nonselection of horizontal *Hk*. Moreover, if it is assumed that the signals applied to input *M* of register *R* are negative logic signals, as are all the other signals, digits 1 and 0 are characterized by levels $-U_2$ and zero respectively.

Consequently, in a matrix comprising, for instance, four horizontals *H1* to *H4*, line *H3* is selected by the transmission, in series form, of the binary number 1011.

The circuit *G'1* delivers a signal *E'k* of amplitude $-U_2$ for the logic condition $E'1 = A11 + A21 + \dots + Aml$.

The inverter *G''1* delivers a signal *E1* of amplitude $-U_2$ for the logic condition $E1 = A11 + A21 + \dots + Aml$.

Signal *E1* therefore indicates that at least one switching circuit associated to the horizontal *H1* is closed: it will hereafter be called *busy signal*.

The connection signal *C1* transmitted by the vertical selection conductor *c1* to the circuits associated to vertical *V1* is also applied to inverter circuit *L1* which delivers signals *C'1*, *C''1*. The switching time of the MOS transistor used to invert the signal has a value *t* and, for instance, when the connection signal is suppressed (transition from condition *C1* to condition *C'1*) signal *C''1* remains present for a time *t*.

FIG. 4 shows a detailed diagram of one of the switching circuits X_{11} , X_{21} , etc. of FIG. 3. Such a circuit which is labeled X_{jk} , comprises the bidirectional cross-point K_{jk} , its control circuit comprising the flip-flop A_{jk} and the NOR circuit P_{jk} . The figure also shows a detailed diagram of the logic circuit G_k associated to horizontal H_k and of the delay circuit L_j associated to the vertical V_j .

In the circuit G_k , the NOR circuit G'_k of FIG. 3 comprises the MOS-Ph transistors T_1 , T_2 ... T_m connected in parallel and R_6 and the inverter G''_k comprises the MOS-Ph transistors T_7 and R_7 . Similarly, the inverter L_j comprises the MOS-Ph transistors T_8 and R_8 .

The NOR circuit P_{jk} which comprises the MOS-Ph transistors T_9 , T_{10} , T_{11} , R_9 is identical to the circuit G'_k and delivers a preselection signal P_{jk} of amplitude $-U_2$ for the logic condition: $P_{jk} = \overline{C'_j} \cdot \overline{S_k} \cdot \overline{E_k} = \overline{C'_j} \cdot \overline{S_k} \cdot \overline{E_k}$.

It can be seen therefore, by referring to table I, that a preselection signal P_{jk} is only present when the following

divided into two parts; the first deals with the effect of the control signals on a nonselected cell and the second describes a specific process for closing the switching circuit X_{jk} located at intersection between vertical V_j and horizontal H_k .

1 Nonselected cells

The lines referenced 1.1, 1.2, 1.3 in table III indicate the signals and voltages on conductors c , c' , s , e and p (NOR circuit P_{jk} output, FIG. 4) in the following cases:

1.1 Rest state (table III, reference 1.1)

10 In the rest state, i.e. when neither the opening or closing of circuit K_{jk} is effected, signals $\overline{C'_j}$ and $\overline{S_k}$ are applied to the selection inputs as well as a signal $\overline{E_k}$ or E_k . Signal $\overline{C'_j}$ blocks the control transistor T_5 of the flip-flop A_{jk} and signals S_k and C'_j block the gate P_{jk} so that the flip-flop is held in position regardless of the voltage level on conductor e_k .

15 It will be noted that, if signal $\overline{S_k}$ is applied when transistor T_5 has been receiving signal $\overline{C'_j}$ for at least a duration t , signal C'_j still blocks gate P_{jk} ,

TABLE III

Ref.	Operation	Conductors						Flip-flop
		c	c'	s	e	p		
1.1	Rest	$\overline{C'_j}$ [0]	C'_j [-U2]	S_k [-U2]	E_k or $\overline{E_k}$	$\overline{P_{jk}}$		
1.2	Vertical half selection	C [-U2]	C' [0]	S [-U2]	E or $\overline{E}$	$\overline{P}$		$\rightarrow \overline{A}$
1.3	Horizontal half selection	$\overline{C}$ [0]	C' [-U2]	$\overline{S}$ [0]	E or $\overline{E}$	$\overline{P}$		
2.1	Horizontal selection	$\overline{C'_j}$ [0]	C'_j [-U2]	$\overline{S_k}$ [0]	$\overline{E_k}$ [0]	$\overline{P_{jk}}$		
2.2	Vertical selection	C_j [-U2]	C'_j [0]	$\overline{S_k}$ [0]	$\overline{E_k}$ [0]	P_{jk}		$\rightarrow \overline{A_{jk}}$
2.3a	Closing	$\overline{C_j}$ [0]	$\overline{C'_j}$ [0]	$\overline{S_k}$ [0]	E_k [0]	P_{jk}		$\rightarrow A_{jk}$
2.3b	Holding	$\overline{C_j}$ [0]	C'_j [-U2]	$\overline{S_k}$ [0]	E_k [-U2]	$\overline{P_{jk}}$		

three conditions are simultaneously fulfilled:

The horizontal H_k is free (condition $\overline{E_k}$)

The horizontal H_k is selected (condition $\overline{S_k}$)

A delayed connection signal is present (condition $\overline{C'_j}$).

The cross-point K_{jk} , located at the intersection of horizontals H' , H'' and of verticals V' , V'' effects the connection between conductors $H'k$ — V'_j and $H''k$ — $V''j$ when the MOS-Ph transistors T_{12} and T_{13} are conducting. The control signal A_{jk} applied to the grids of the said transistors is delivered by the flip-flop bearing the same reference. This holding flip-flop comprises the MOS-Ph transistors T_3 , T_4 , T_5 , T_6 , R_4 and R_5 .

The operation of such a flip-flop in which transistors T_5 and T_6 are used to control the switching, is similar to that of a flip-flop equipped with PNP bipolar transistors and will not be described in detail.

Table II, below, indicates the state of transistors T_3 and T_4 when the flip-flop is in the 1 and in the 0 states as well as the state of the cross-point K_{jk} and the drain voltages of said transistors.

The grids of control transistors T_5 and T_6 are either brought to potential $-U_2$ (logic conditions C_j , P_{jk}) or to ground potential (logic conditions $\overline{C_j}$, $\overline{P_{jk}}$). It can be seen that, for the logic condition C_j , transistor T_5 is conducting and that flip-flop A_{jk} is set in the 0 state (logic condition A_{jk}) and that, in condition P_{jk} , it is set in the 1 state (logic condition A_{jk}).

It will be noted that if transistors T_5 and T_6 are simultaneously conducting through the application of signals C_j and P_{jk} , the drains of transistors T_3 and T_4 are both brought to ground potential and that a signal A_{jk} appears.

1.2 Application of a connection signal (table III, reference 1.2)

35 The application of signal C_j on the vertical selection conductor c_j produces the opening of all the cross-points associated to the vertical V_j . In fact, said signal makes all transistors T_5 conducting and flip-flops A are set in the 0 state. Line 1.2 of table III represents the various voltages in the case of nonselected horizontals (signal S).

1.3 Application of a selection signal (table III reference 1.3)

When the horizontal H_k is selected by applying the signal $\overline{S_k}$, the nonselected verticals receive a signal $\overline{C}$ and, as can be seen, each gate P remains blocked provided that signal $\overline{C}$ has been applied for at least a time t before signal $\overline{S_k}$.

2 Closing of a cross-point

There follows a description, given by way of a nonlimitative example, of a process for closing circuit X_{jk} assuming that the voltages initially applied corresponded to the rest state (table III, reference 1.1) and that the horizontal H_k is free, i.e. that a signal $\overline{E_k}$ is standing on conductor e_k . The said closing process comprises the following operations carried out in time succession.

55 2.1 Horizontal selection (table III, ref. 2.)

Signal $\overline{S_k}$ is applied to conductor s_k . As signal C'_j is present, gate P_{jk} is blocked and flip-flop A_{jk} does not switch.

2.2 Vertical selection

A signal C_j is applied to conductor c_j so that flip-flop A_{jk} resets in the 0 state (condition $\overline{A_{jk}}$). After a delay t , circuit L_j delivers a signal $\overline{C'_j}$ and, if the horizontal is free—this being characterized by the signal $\overline{E_k}$ —signal P_{jk} appears so that the drains of transistors T_3 and T_4 are both grounded (table III,

TABLE II

State of the flip-flop	State of the transistors		State of the cross-point	Voltage levels	
	T3	T4		Output 1 (drain of T3)	Output 0 (drain of T4)
1 state	Blocked	Conducting	Closed	$-U_2$ (signal A_{jk})	0
0 state	Conducting	Blocked	Open	0 (signal $\overline{A_{jk}}$)	$-U_2$

There follows a description—with reference to table II—of the operation of the multiselector of FIG. 3. This description is

75 ref. 2.2). Transistors T_{12} and T_{13} (FIG. 4) are blocked and the cross-point is still open (condition A_{jk}).

2.3 Closing of the cross-point

The signal C_j is suppressed (condition $\bar{C}_j$) however, signal $\bar{C}'_j$ remains for a time t . Transistor T_3 is therefore blocked whereas transistor T_4 remains conducting under the control of the signal P_{jk} (table III, ref. 2.3a)

Consequently flip-flop A_{jk} is set in the 1 state (condition A_{jk}) making transistors T_{12} and T_{13} conducting: the cross-point is closed and a signal E_k appears which blocks the gate P_{jk} (signal $\bar{P}_{jk}$). After a time t , signal B'_j is also produced (table III, ref. 2.3b): the cross-point is held in a closed position.

2.4 End of operation

The signal $\bar{S}_k$ is suppressed (condition S_k) and the device is at rest. (table III ref. 1.1).

While the principles of the above invention have been described in connection with specific embodiments and particular modifications thereof it is to be clearly understood that this description is made by way of example and not as a limitation of the scope of the invention.

In particular, opposite polarity transistors can be used by inverting the polarities of the power supply sources.

We claim:

1. An electronic switching circuit comprising a matrix formed by a first plurality of conductors and a second plurality of conductors intersecting at a plurality of cross-points, each cross-point including an MOS transistor having grid and source and drain electrodes, means coupling said source and drain electrodes to conductors which are to be intercon-

nected, each cross-point comprising a control circuit including a flip-flop having 1 and 0 outputs and incorporating MOS transistors, means coupling the 1 output of each said flip-flop to the grid electrode of an MOS transistor causing it to conduct when the flip-flop is in the 1 state and causing it to block when the flip-flop is in the 0 state

5 2. An electronic switching circuit as claimed in claim 1, in which there are means individual to each of said first plurality of conductors for resetting the flip-flop by applying a connection signal to its input and an electronic gate is coupled to each of the conductors of said first plurality for setting the flip-flop by applying a setting signal when the gate receives signals indicating resetting is in order.

10 3. An electronic switching circuit as claimed in claim 1 in which the first and second pluralities of conductors in the matrix comprise respectively m verticals and n horizontals with which the respective selection conductors are associated, means coupled to each conductor of said first plurality for accepting a signal over a selected horizontal to establish conditions for closure of the corresponding cross-point, said matrix including m delay conductors coupled to the verticals and n busy state conductors coupled to the horizontals and means supplying signals over respective delay conductors and busy state conductors to hold the flip-flop in an unchanged status.

15 4. An electronic switching circuit as claimed in claim 1, in which there is a shift register commonly coupled to the conductors of said second plurality whereby outputs of said shift register are employed to control selections in the matrix.
